DESIGN FOR A COMBINED ELECTRIC MOTOR AND POWER UNIT FOR ELECTRIC FOOD DEVICES

Hermann M. Alfred Strauss, Chicago, Ill., assignor to A. F. Dormeyer Mfg. Co., Chicago, Ill., a corporation of Illinois

Application September 2, 1938, Serial No. 79,685

Term of patent 14 years

To all whom it may concern:

Be it known that I, Hermann M. Alfred Strauss, a citizen of the German Republic, residing at Chicago, in the county of Cook and State of Illinois, have invented a new, original, and ornamental Design for a Combined Electric Motor and Power Unit for Electric Food Devices, of which the following is a specification, reference being had to the accompanying drawing, forming part thereof.

Fig. 1 is a side elevational view of a combined

electric motor and power unit for electric food devices, embodying my new design;

Fig. 2 is a front elevational view thereof;

Fig. 3 is a rear elevational view thereof;

Fig. 4 is a top plan view thereof;

Fig. 5 is a bottom plan view thereof.

I claim:

The ornamental design for a combined electric motor and power unit for electric food devices, as shown.

HERMANN M. ALFRED STRAUSS.
